UNITED STATES PATENT OFFICE.

WILLIAM O. LATTA AND JOHN A. PLUNK, OF MICHIE, TENNESSEE.

FOLDING CRATE.

Application filed October 3, 1922. Serial No. 592,051.

To all whom it may concern:

Be it known that we, WILLIAM O. LATTA and JOHN A. PLUNK, citizens of the United States, residing at Michie, in the county of 5 McNairy and State of Tennessee, have invented certain new and useful Improvements in a Folding Crate; and we do hereby declare the following to be a full, clear, and exact description of the invention, such as 10 will enable others skilled in the art to which it appertains to make and use the same.

The object of the invention is to provide a comparatively simple and strong and therefore durable shipping crate, suitable 15 for poultry and other products which may be folded into compact form for return shipment to the producer and which can readily be folded and extended and of which all of the elements or members are connected 20 together without any detachable features which can become misplaced or lost and which when folded can be locked in that condition so that injury may not occur to the parts thereof when in the knock-down 25 condition; and with these objects in view the invention consists in a construction, combination and relation of parts of which a preferred embodiment is shown in the accompanying drawings, wherein:

30 Figure 1 is a view in side elevation of a crate embodying the invention in the operative or shut-up condition,

Figures 2 and 3 are respectively longitudinal and transverse sectional views of the 35 same, on the lines 2—2 and 3—3 of Figure 4,

Figure 4 is a plan view,

Figure 5 is a longitudinal sectional view 40 of the crate in its folded condition, Figure 6 is a sectional view on the line 6—6 of Figure 5,

Figure 7 is a detail sectional view on the line 7—7 of Figure 4, and

Figure 8 is a sectional view of one of the bearings or hinge eyes.

45 The crate consists essentially of a base or bottom 10, inwardly foldable end walls 11, inwardly foldable side walls 12 and a top wall 13 which may be provided with the usual door 14 yieldingly held closed by 50 a spring 15 and provided with a latch 16.

The end walls are provided with bottom hinge rods 17 mounted in bearing eyes 18, and coiled springs 19 are preferably used in connection therewith for holding the end 55 walls in their upright position, but said walls may be folded into parallelism and

contact with the bottom wall or base where they may be firmly secured by turn buttons 20 swiveled on the base or bottom wall. The actuating springs for the end walls 60 impart an outward swinging or extending impulse thereto.

The side walls are provided with bottom hinge rods 21 engaged by coiled springs 22 which impart an outward or spreading impulse to said walls, so that when released the side walls are spread or expanded by 65 their actuating springs. The side walls are provided with terminal parallel sided links 23 of a length corresponding with the width 70 of said walls and the top wall is provided at its ends with horizontal depending parallel sided links 24 with which the links at the ends of the side walls have an interlocking sliding connection so that the links 75 of the top wall serve as a means for limiting the outward swinging movement or expansion of the side walls. As the crate is folded, the side walls being swung inwardly and the top wall moving downwardly, the 80 interlocking links of the side and top walls slide with relation to each other, the side walls ultimately lying upon the end walls and the top wall covering the inwardly 85 folded side walls, whereupon the top wall 85 is secured to the base or bottom wall by a locking device consisting of a rock shaft 25 provided with hooks 26 for engaging eyes 27 on the base or bottom. At an intermediate portion of its length the rocker 90 shaft is provided with a latch arm 28 having a terminal spring tongue 29 for engaging one of the longitudinal rods 30 of the top wall to secure the hooks in interlocking engagement. Upon releasing the latch arm 95 and turning the rocker shaft to disengage said hooks the crate is expandable without further manipulation on the part of the operator by the outwardly folding action 100 of the side walls which serve to raise the top wall, and the elevation of which is limited by the engagement of the upper ends of the links of the side walls with the extremities of the links of the top wall, while upon the disengagement of the turn buttons from the 105 end walls the latter are folded outwardly until their movement is checked by contact with the depending links on the ends of the top walls which constitute stops for said end walls. The end walls may be locked in their 110 position and the other members of the crate secured against displacement by the return

of the rock shaft to its normal position whereupon the hooks thereof swing downward into the paths of inward movement of the upper edges of the end walls and hold them in place. Thus both side and end walls of the crate are yieldingly actuated to swing outward or expand and the top wall is carried by the side walls and has a sliding connection therewith so as to be elevated by the expansion or outward swinging movement of the side walls, all of said walls being foldable into parallelism with the base where they may be secured in compact relation for return shipment and storage.

15. Having thus described the invention, what I claim is:

1. A folding crate having a base, inwardly foldable end and side walls and a top wall carried by the side walls and having an interlocking sliding connection at its extremities with said side walls, the side walls having outwardly swinging or expanding actuating springs.

2. A folding crate having a base, inwardly foldable end and side walls and a top wall carried by the side walls and having an interlocking sliding connection at its extremities with said side walls, the side walls having outwardly swinging or expanding actuating springs, and means carried by the top wall for locking the same in its folded position.

3. A folding crate having a base, inwardly foldable end and side walls and a top wall carried by the side walls and having an interlocking sliding connection at its extremities with said side walls, the side walls having outwardly swinging or expanding actuating springs, and a rock shaft carried by the top wall and having hooks for engaging eyes on the bottom wall.

4. A folding crate having a base, inwardly foldable end and side walls and a top wall carried by the side walls and having an interlocking sliding connection at its extremities with said side walls, the side walls hav-

ing outwardly swinging or expanding actuating springs, and a rock shaft carried by the top wall and having hooks for engaging eyes on the bottom wall, said rock shaft having a latch arm for engaging an element of the top wall to hold the rock shaft in its locking position.

5. A folding crate having a base, inwardly foldable end and side walls and a top wall carried by the side walls and having an interlocking sliding connection at its extremities with said side walls, the end and side walls being provided with outwardly swinging actuating springs, and means for securing the end walls and means for securing the top wall in folded relation with the base.

6. A folding crate having a base, inwardly foldable end and side walls and a top wall carried by the side walls and having an interlocking sliding connection at its extremities with said side walls, the side walls having outwardly swinging or expanding actuating springs, and a rock shaft carried by the top wall and having hooks for engaging eyes on the bottom wall, said hooks serving to lock the end walls in their extended positions.

7. A folding crate having a base, inwardly foldable end and side walls and a top wall carried by the side walls and having an interlocking sliding connection at its extremities with said side walls, said side walls provided with outwardly swinging actuating springs, means for securing the end walls in folded condition, and independent means for securing the top wall in folded relation with the base.

In testimony whereof we affix our signatures in presence of two witnesses.

WILLIAM O. LATTA.
JOHN A. PLUNK.
